UNITED STATES PATENT OFFICE

RICHARD HOWLAND RANGER, OF BROOKLYN, NEW YORK, ASSIGNOR TO RADIO CORPORATION OF AMERICA, A CORPORATION OF DELAWARE

INTERFERENCE-REDUCING MEANS FOR RADIO RECEIVING APPARATUS

Application filed December 18, 1922. Serial No. 607,478.

This invention relates to improved means for combining signals received from the same station on a plurality of aerials, and more specifically, to means for controlling the space current in a vacuum tube detector or amplifier in accordance with such signals, in such a way that the tubes will respond only to signals which have a predetermined phase relationship.

10. It is an object of this invention to provide such means which will decrease the interfering effects caused by static disturbances and which will also reduce the interfering effects caused by the operation of another transmitting station on substantially the same wave length as the station desired. It is a further object of this invention to provide means for geographically tuning to select one particular transmitting station 15 from among several transmitting on substantially the same wave length. It is a further object of this invention to provide such means which shall have a sharper tuning characteristic than the arrangements now used for 20 the purpose, and which shall, at the same time, be relatively inexpensive, simple to construct and install and which shall be reliable and positive in its operation. Still other objects will be apparent from the specification.
25. My invention is shown by way of example in the accompanying drawing and is explained in the specification with reference to the embodiment illustrated and its underlying principles will best be understood by 30 reference to the specification and drawing but the scope will be particularly pointed out in the accompanying claims.

Referring to the drawing,

35. Figure 1 is a diagram showing the relative position of sending, receiving and recording stations.

Figure 2 is a diagrammatic comparison of the addition law of an arrangement old in the art as shown in dotted lines and of my invention as shown in full lines.

Figure 3 is a diagram of the circuit embodying my invention and

Figure 4 is a diagrammatic elevation view of the filament and grid of a vacuum tube according to my invention.

Figure 5 is a plan view of the same.

Referring to Figure 1, let A represent a transmitting station, B and B' two receiving stations connected by wire lines to the common indicating apparatus at C and let D be a second transmitting station. It is well known in the art that as a wave from station A travels along, as shown in dotted lines, it will first be taken up at station B and later be taken up at B'. This difference in time may be very small but it is, nevertheless, sufficient for certain arrangement of the receiving station with reference to the transmitting station, to produce large difference in phase at the indicating apparatus C where the signals are combined. It has been suggested that in order to obtain maximum signal response from the desired transmitting station the signals should be brought into phase with each other and added together and the resultant signal thereby obtained utilized to actuate the detector. It has further been suggested that this adjustment of phase may be accomplished by the use of phase rotators or phase shifting coils in one or both lines.

It has been found that as the signals are brought into phase they add according to the law of cosines giving a curve such as shown in dotted lines in Fig. 2. It will be seen by an inspection of this curve as well as by the application of trigonometry that for signals which are out of phase by a substantial amount the response may be almost as great as if the signals were absolutely in phase. While this arrangement is satisfactory when the signals from the interfering station have a relatively large phase difference it will not prevent interference when the phase difference of the signals is relatively small.

My invention provides means for overcoming this difficulty and achieving a resultant curve such as shown in full lines in Figure 2. It will be seen by comparison of the curves of Figure 2 that by the use of apparatus having the characteristic shown in full lines, it is possible to obtain much greater selectivity as regards interfering stations when the interfering station is situated relatively close to the desired transmitting station so that the phase difference between signals

from the interfering station is not greatly different from the phase difference of signals from the desired station.

It has been found in practice that when 5 one of the wires in the grid of a detector or amplifier tube is cut out the efficiency drops off to a very much greater extent than would be expected. For instance, if a grid consists of 10 parallel sections of wire and one 10 of these sections breaks; the drop in efficiency is considerably over 10%. I make use of this phenomenon to provide that no response will be obtained from the indicating apparatus unless the signals received at the common 15 indicating device have a desired and predetermined phase relation and this is done as follows:

Referring to Figure 3, B and B' respectively designate two receiving aerials having 20 different characteristics in one or more respects. For instance, they may be located at different distances from the transmitting station, or they may have different directional characteristics or they may have different 25 electrical characteristics, with reference to tuning, damping etc. Each aerial is provided with the usual tuning means such as, variable inductances 1 and 1' and variable condensers 2 and 2'. The signals received 30 upon these aerials may be amplified by the use of any suitable means known in the art if desired or they may be transmitted over the wire lines to the indicating apparatus at C without amplification, depending upon 35 circumstances. The indicating apparatus provided at C comprises a multiple section grid amplifier tube designated as 3. This tube comprises a hot cathode and an anode according to the well known construction 40 but is provided with a plurality of electrical- ily independent grids 4 and 4'. I preferably arrange these grids as diagrammatically shown in Figs. 4 and 5, in such a way that each horizontal section of the grid is in the 45 form of an ellipse enclosing the filament, this section being attached at one end to the conducting post P, which leads to a contact stud (not shown) in the base of the tube. As shown by Fig. 4 the sections of the grid 50 are connected alternately to posts P and P', the post P' also leading to another contact stud in the base of the tube. The signals received from station B are impressed across the cathode of tube 3 and the grid 55 4 whereas signals from station B' are impressed across the cathode of the tube 3 and the grid 4'. Connected in the output circuit of this amplifier I provide a coupling coil 5 for the purpose of impressing the combined signal from amplifier 3 upon a suitable detector 6 provided with any suitable indicating or recording means, herein shown as telephone receivers 7. The amplifier tube 3 is operated at such point of its character- 60 istic that the combined action of grids 4

and 4' is required to render it operative; that is to say signals must be in phase on grids 4 and 4' in order to produce response of the amplifier.

Turning now to the operation of my receiving apparatus, if it is desired to receive signals from station A the phase shifting means 70 will be so adjusted as to bring the signals from A into phase with each other at C as pointed out above. This condition corresponds to maximum response of the indicating apparatus. Let it now be assumed that it is desired to receive signals from station D. The phase shifting means will be adjusted to bring signals from this station into 75 phase at C. It will be apparent that signals received from station A will no longer be in phase at C and therefore will not be reproduced in the output circuit of the amplifier and hence will not affect the indicating or recording apparatus. 80

It will be seen that I have provided means whereby the combined action of both aerials giving oscillations having predetermined phase relation is required to cause response 85 of the indicating or recording means. This property is of advantage in preventing response of the indicating means to static disturbances since it will be apparent that the only static disturbance which can be passed 90 through the amplifier 3 is a disturbance which has the same phase relationship as that of the signal desired and it will be seen also that this will prevent disturbance due 95 to any signal or static which is received upon 100 only one antenna.

While I have shown and described tube 3 as an amplifier, it will be apparent that similar results may be obtained by operating this tube as a detector, and that the number of aerials to be used may be increased by providing a grid section for each aerial. Still other modifications and changes may be made as will be apparent to anyone skilled 105 in the art without departing from the spirit 110 of my invention.

Having described my invention I declare that what I claim is:

1. In radio signalling apparatus the combination of a plurality of aerials, a common 115 receiving means for all of said aerials, a multiple grid vacuum tube forming a common means for receiving oscillations received on said aerials, means for connecting each of said aerials to a separate grid member 120 of said tube, and means for applying the signal energy received on said aerials to said various grid members in a like phase relationship.

2. In radio signalling apparatus the combination of a plurality of aerials spaced apart a considerable fraction of a wave-length, a vacuum tube having a plurality of grid members each connected to a different aerial, a phase control means for controlling the phase 125 130

- relationship of the signal energy received on all of said aerial members and thereby impressing the said signal energy upon all grids simultaneously in like phase relationship and indicating means operatively associated with the output circuit of said tube. 5
3. In radio signalling apparatus the combination of a plurality of aerials, a common amplifying means for said aerials, said amplifying means comprising a vacuum tube having a grid composed of a plurality of sections, each section of said grid being connected to a different aerial. 10
4. In radio signalling apparatus a plurality of aerials, common amplifying means for said aerials, said amplifying means comprising a vacuum tube having a grid composed of a plurality of sections, each section being connected to a different aerial, and indicating means connected in the output circuit of said amplifier. 15
5. In radio signalling apparatus the combination of a plurality of aerials, common amplifying and detecting means, said means comprising a vacuum tube having a grid made up of a plurality of separate sections, each section being connected to a different aerial, phase control means for impressing energy of like phase relationship simultaneously upon each of said grid sections and indicating means connected in the output circuit of said amplifying and detecting means. 20
6. In radio signalling apparatus the combination of a plurality of aerials spaced apart a fraction of the signal wave-length and a common detecting and amplifying means associated with said aerials, said detecting and amplifying means comprising a vacuum tube having multiple grid members and responsive only to the combined in-phase signal energy received on all of said aerials. 25
7. In radio signalling apparatus the combination of a plurality of spaced aerials, a vacuum tube detector comprising a plurality of grids each connected to a different aerial means for impressing signal energy of like phase relationship from each aerial upon said grids, and indicating means operatively associated with the output circuit of said tube. 30
8. The method of operating a vacuum tube in response to signals received on a plurality of aerials spaced apart a considerable fraction of a wave-length of the signals received which comprises subjecting the space current of the tube simultaneously to the control of signal potential from each aerial independently. 35
9. The method of reducing interference in the reception of radio signals which comprises receiving the signal on two aerials separated by a considerable distance, and controlling the space current of a vacuum tube simultaneously and independently by the signal potential from each aerial. 40
10. The method of reducing interference in radio signal reception which comprises, receiving signals on a plurality of aerials spaced a considerable fraction of a wavelength apart, tuning all of said aerials to the same signal frequency, controlling the phase relationship of the signal received upon each aerial with respect to each other aerial, and controlling the space current in a common amplifying tube simultaneously from the signal energy received on all of said aerials. 45

CERTIFICATE OF CORRECTION.

Patent No. 1,738,392.

Granted December 3, 1929, to

RICHARD HOWLAND RANGER.

It is hereby certified that error appears in the printed specification of the above numbered patent requiring correction as follows: Page 3, line 18, claim 4, after the word "aerial" insert the words "phase control means for impressing energy of like phase relationship simultaneously upon each of said grid sections,"; same page, lines 28 to 30, claim 5, strike out the words "phase control means for impressing energy of like phase relationship simultaneously upon each of said grid sections"; and that the said Letters Patent should be read with these corrections therein that the same may conform to the record of the case in the Patent Office.

Signed and sealed this 22nd day of April, A. D. 1930.
